ABSTRACT

A displacement type pilot valve in which an exhaust valve and an air supply valve are both enabled free to get into and out of an output pressure chamber, thereby improving the response performance of the valve rod provided on its opposite ends with said exhaust valve and air supply valve.

DISPLACEMENT TYPE PILOT VALVE

BACKGROUND OF THE INVENTION

1. Field of the Invention

The present invention relates to a displacement type 5 pilot valve used as a pneumatic amplifier in a pneumatic measuring and controlling instrument.

2. Description of the Prior Art

Two kinds of pilot valves have been known in the art one of which is a displacement type pilot valve and the other of which is a force-balance-type pilot valve. Now the difference between the displacement type and the force balance type will be described hereinbelow.

FIG. 1 shows a principle and basic construction of the prior art displacement type pilot valve, and FIG. 2 15 shows a block diagram representing the performance of the pilot valve shown in FIG. 1.

Referring to FIG. 1, the reference numeral 1 shows a casing of the pilot valve, 2 shows a pressure receiving member such as a diaphragm for moving by virtue of 20 input pressure P_N , a valve rod 9 and an exhaust valve portion 3 integrally fixed to the valve rod 9 to form an air passage on the exhaust side, 4 shows an air supply valve interposed between the valve rod 9 and the push spring 11 to form an air passage on the air supply side, 5 shows an exhaust valve seat to form an exhaust air 25 passage together with the exhaust valve 3, 6 shows a supply valve seat to form an air supply passage together with the supply valve 4, 7 shows an input pressure chamber, 8 shows an air supply chamber, 12 shows an output chamber for transmitting an output pressure P_o , and the reference numeral 10 shows an exhaust chamber 30 leading to the atmospheric pressure P_A .

In the construction as described above, an input pressure P_N is exerted on the pressure receiving member 2 and is converted into a force F_t , and the force F_t in turn acts against the spring force (composed force of the spring force of the push spring 11 and the elastic force of the diaphragm 2) and move the exhaust valve 3 and the supply valve 4. By the movement of the supply valve and exhaust valve, the spacing between the valves 3 and 4 and the valve seats 5 and 6 varies which results in variation in the amount of flow from the supply chamber 8 to the output pressure chamber 12 and the amount of flow from the output pressure chamber 12 to the exhaust chamber 10. Based on the variation in the amount of flow, the output pressure P_o varies. The pilot valve having such construction and function as described above is called displacement type pilot valve.

It will be noted that in the displacement type pilot valve the output pressure P_o is determined by the difference between the amount of the air supply from the spacing formed with the supply valve 4 and the supply valve seat 6 and the amount of the exhaust flow passing through the spacing formed with the exhaust valve 3 and the exhaust valve seat 5.

Referring to FIG. 2 showing a block diagram of the performance of the pilot valve shown in FIG. 1, the reference character P_N shows an input pressure exerted on the pressure receiving member 2, A_D shows an effective area of the pressure receiving member 2, S_1 shows a spring constant (kg/cm), KQ_1 shows a coefficient represented by the ratio of the output pressure and the displacement of the valve for the output pressure. As apparent from the drawing, one of the features of the displacement type pilot valve is that there is no feed-back means.

FIG. 3 shows a principle and basic construction of the prior art force-balance-type pilot valve, and FIG. 4 shows a block diagram representing the performance of the pilot valve shown in FIG. 3.

Now, when an input pressure P_N is exerted on the input pressure receiving member 202 in the force balance type pilot valve as shown in FIG. 3, the input pressure P_N is converted into the force F_t , and the force F_t acts against the composed spring force (composed force of the elasticity of the input pressure receiving member 202, the elasticity of the output pressure receiving member 204 and the spring force of the push spring 206) and moves the exhaust valve rod 203 and the supply valve 205.

When the input pressure P_N becomes positive with respect to the balanced pressure by the movement of the exhaust valve 203 and the supply valve 205, a spacing is made between the supply valve 203 and the supply valve seat 205 and no spacing is made between the valve 205 and the exhaust valve seat 208. On the contrary, when the input pressure becomes negative with respect to the balanced pressure, a spacing is made between the supply valve 205 and the exhaust valve seat 208 and no spacing is made between the supply valve 205 and the supply valve seat 207. Now, in the case that the input pressure P_N becomes positive with respect to the balanced pressure, the supply valve 205 is pushed downward in the drawing and the supply pressure P_S makes the air flow from the supply pressure chamber 211 to the output pressure chamber 210 and the output pressure P_o increases. The output pressure P_o is exerted on the output pressure receiving member 204 and the pressure receiving member 204 is urged in the opposite direction to that of the action of the supply pressure P_N , which results in closing of the supply valve 205 and the supply valve seat 207. Then, when the force F_t made by the supply pressure P_N exerted on the supply pressure receiving member 202 becomes equal to the force F_o made from the output pressure P_o exerted on the output pressure receiving member 204, the supply valve 205 is brought into closed contact with the supply valve seat 205, the supply valve seat 207, and the exhaust valve seat 208. Thus, the pilot valve comes into the balanced condition.

Further, when the input pressure becomes negative with respect to the balanced pressure, a spacing is made between the supply valve 205 and the exhaust valve seat 208 as described above, and the air within the output pressure chamber 210 is discharged into the atmosphere through the exhaust pressure chamber 209. Then, when the force F_t made by the supply pressure P_N exerted on the supply pressure receiving member 202 becomes equal to the force F_o made by the output pressure P_o exerted on the output pressure receiving member 204, the supply valve 205 is brought into contact with the supply valve seat 207 and the exhaust valve seat 208. Thus, the pilot valve is made to be balanced.

In short, the output pressure P_o is determined by the difference between the amount of the air supply from the spacing formed with the supply valve 205 and the supply valve seat 207 and the amount of the exhaust flow passing through the spacing formed with the exhaust valve seat 208 and the supply valve 205 in the force balance type pilot valve. In this type of the pilot valve, the force exerted on the input pressure receiving member is balanced with the spring force of the input

pressure receiving member, the supply valve push spring and the output pressure receiving member. Another feature of the force balance type pilot valve is that when the pilot valve is balanced, the supply valve 205 is brought into closed contact with the supply valve seat 207 and the exhaust valve seat 208. The balanced condition referred to herein means the condition where $F_t = F_0$, wherein $F_t = (\text{input pressure } P_N) \times (\text{effective area of the input receiving member } 202 A_B)$ and $F_0 = (\text{output pressure } P_0) \times (\text{effective area of the output receiving member } 204 A_B)$.

FIG. 4 is a block diagram representing the performance of the valve shown in FIG. 3. Referring to FIG. 4, the reference character S_2 shows a spring coefficient of the whole system of the pilot valve shown in FIG. 3 and the reference character KQ_2 shows a coefficient of the displacement of the valve for the output pressure P_0 which is determined by the ratio of the output pressure and the displacement of the valve for the output pressure. The reference character A_B shows an effective area of the output pressure receiving member. One of the features of the force balance type pilot valve is that there is a feedback effect.

As described above, the displacement type pilot valve has no feedback means and accordingly is of the bleed type. On the other hand, the force balance type pilot valve has a feedback means and accordingly is of the nonbleed type.

Based on the above difference in the feedback system, the amount of consumption of the air is different in the type of pilot valve. That is, in the displacement type pilot valve the air consumption is about 0.2 to 1.5 Nm^3/h , while it is about 0.02 to 0.4 Nm^3/h in the force balance type pilot valve. With respect to the amount of the air consumption, the force balance type pilot valve is more advantageous, accordingly.

However, in the sense of construction, the force balance type is less advantageous than the displacement type one, since a complex construction is required in the force balance type pilot valve such as an output receiving member 204 provided between the output pressure chamber 210 and the exhaust pressure chamber 209 and a bottomed slot provided in the exhaust valve rod connected to the exhaust pressure chamber 209.

SUMMARY OF THE INVENTION

A principal object of the present invention is to provide a displacement type pilot valve having a simple construction as of the prior art pilot valve of this type and at the same time having an effect of reducing the amount of air consumption.

In addition to the aforementioned disadvantage that the amount of air consumption is large in the displacement type pilot valve, this type of pilot valve is also disadvantageous in that the response speed is slow and further the response time in case that the output pressure increases is different from that in case that the output pressure decreases.

Therefore, the second object of the present invention is to provide a displacement type pilot valve which has a quick response.

The third object of the present invention is to provide a displacement type pilot valve which has a constant response time of the valve in both cases where the output pressure increases and decreases.

The fourth object of the present invention is to provide a displacement balance type pilot valve which will

not be affected by the fluctuation in the supply pressure.

In accordance with the present invention, there is provided a displacement balance type pilot valve comprising a casing including an input pressure chamber to which the input is led in, an exhaust pressure chamber leading to the atmosphere and an output pressure chamber compartmented from the input pressure chamber with a diaphragm, an air supply pressure chamber to which air is supplied and an output pressure chamber connected to the air supply pressure chamber and the exhaust pressure chamber for transmitting the output pressure out, a valve rod integrally connected with a valve to be disposed in the passage from the output pressure chamber to the exhaust pressure chamber at an end thereof and integrally connected with a valve to be disposed in the passage from the air supply pressure chamber to the output pressure chamber at the other end thereof, said valve to be disposed in the passage from the output pressure chamber to the exhaust pressure chamber being secured to said diaphragm, and a push spring forwarding said valve rod to said diaphragm, wherein the output pressure chamber and the valve rod are so constructed as to satisfy the formulae

$$d_2 > d_1, \text{ and } l_1 \geq l_2,$$

where d_2 is a diameter of the output pressure chamber, l_2 is the height thereof, d_1 is a diameter of the valve rod, and l_1 is the length of the valve rod including the valves fixed at the both ends thereof.

BRIEF DESCRIPTION OF THE DRAWING

FIG. 1 is a vertical cross sectional view of the conventional displacement type bleed pilot valve,

FIG. 2 is a block diagram showing the performance of the pilot valve shown in FIG. 1,

FIG. 3 is a vertical cross sectional view of the conventional force balance type nonbleed pilot valve shown in schematic representation,

FIG. 4 is a block diagram showing the performance of the pilot valve shown in FIG. 3,

FIG. 5 is a vertical cross sectional view showing an embodiment of the pilot valve in accordance with the present invention,

FIG. 6 is an enlarged detail view in section of the valve and valve seat portion of the pilot valve shown in FIG. 5,

FIGS. 7A through 7C show the operation of the valve portion of the pilot valve shown in FIG. 5,

FIGS. 8A through 8D show different modified embodiments of the pilot valve in accordance with the present invention,

FIG. 9 is a schematic vertical sectional view of still another embodiment of the pilot valve in accordance with the present invention,

FIG. 10 is a graphical representation showing characteristics of the displacement type semibleed pilot valve in accordance with the present invention in comparison with the conventional displacement type bleed pilot valve,

FIG. 11 is a diagrammatic representation showing a feedback system including a pilot valve employed in a pneumatic measuring instrument or a controller,

FIG. 12 is a schematic sectional view of the pilot valve in accordance with the present invention shown together with the relevant system in one application of the pilot valve of the present invention,

FIGS. 13A through 13C are graphical representation of the characteristics of the pilot valve of the invention showing the influence of the flapper and nozzle to the output pressure of the pilot valve according to the fluctuation of the air supply,

FIG. 14 is a graph showing a characteristic curve representing the relation between the air supply pressure and the output pressure in the pilot valve, and

FIG. 15 is a graphical representation of the characteristic curves of the pilot valve in accordance with the present invention not affected by the fluctuation in the air supply pressure.

DESCRIPTION OF THE PREFERRED EMBODIMENTS

FIG. 5 shows an embodiment of the pilot valve in accordance with the present invention in a sectional view. Referring to FIG. 5, the reference numeral 501 shows a casing of the valve, 502 shows a pressure receiving member such as a diaphragm for moving a valve rod 503 by the input pressure P_N , 504 shows an exhaust valve to form an air passage on the exhaust side, 505 shows an air supply valve forming an air passage on the air supply side, 506 an exhaust valve seat forming an exhaust passage together with the exhaust valve 504, 507 an air supply valve seat to form an air supply passage together with the supply valve 505, 508 an input pressure chamber, 509 an air supply pressure chamber, 510 an output pressure chamber, 511 an exhaust pressure chamber, 512 a push spring to push the valve rod 503 toward the diaphragm, the reference character P_S shows a supply pressure, P_N an input pressure, P_0 an output pressure and P_A shows atmosphere.

FIG. 6 shows a detailed construction of the valve and valve seat portion of the pilot valve shown in FIG. 5 and FIGS. 7A to 7C show the operation of the valve portion. FIG. 7A shows the valve portion in the state where the input pressure is not yet balanced, FIG. 7B shows the valve portion in the state of balancing, and FIG. 7C shows the valve portion in the state that the excessive input pressure is exerted on the valve portion.

In FIGS. 6 and 7A to 7C, the reference numeral 513 shows an air supply passage formed with an air supply valve 505 and the air supply valve seat 507, 514 shows an exhaust leakage spacing formed with the valve rod 503 and the valve seat 519 to determine the amount of bleed at the time of balancing, 515 (FIG. 7) shows an air supply leakage spacing formed with the valve rod 503 and the valve seat 519 to determine the supply leakage before the balancing, and the reference numeral 516 shows an air supply passage formed with the air supply valve 505 and the supply valve seat 507 for passing the supplied air at the time when an excessive input pressure is exerted on the valve portion.

Further, one of the features of the valve of the present invention is that the dimension of the valve portion is made so that the relationship as $d_2 > d_1$ and $l_1 \geq l_2$ is satisfied, where d_2 is the diameter of the output pressure chamber 510 of the casing 501, l_2 is the height thereof, d_1 is the diameter of the valve rod, l_1 is the length of the valve rod including the valves fixed to the end portions thereof as shown in FIG. 6.

Now, when the input pressure P_N enters into the input pressure chamber 508 and the valve is brought into the balanced condition, the diaphragm 502 pushes the valve rod 503 downward by the pressure. Then the valve rod 503 is stopped at the position where the elas-

ticity of the diaphragm 502 is balanced with the spring force of the spring 512. Such a balanced situation is shown in FIG. 7B. Thus, the amount of the air supply Q_0 and the exhaust leakage Q_A are determined by the size of the air supply passage 513 and the exhaust leakage spacing 514 which are in turn determined by the position of the valve rod 503. Thus, the output pressure P_0 is controlled by the input pressure P_N .

While the input pressure P_N is not yet balanced with the air supply, the air supply pressure P_S is exerted on the sectional area of the valve rod 503 and the pushes the valve rod 503 upward cooperating with the spring 512, and the air supply passage 513 forms an air supply leakage spacing 515 and the exhaust passage 518 as shown in FIG. 7A. Under such a situation, the amount of the air supply is made extremely small and the amount of the exhaust air is increased, which results in improvement in the response of the valve at the time of the exhaust.

In the event that an excessive input is provided into the input pressure chamber 508, the air supply passage 513 is broadened as indicated by 516 in FIG. 7C and the exhaust leakage spacing 514 increases its resistance and accordingly the exhaust leakage is decreased by a similar effect as that described above in the explanation of the unbalanced situation.

By the above operation, that is by the construction wherein the exhaust passage is normally narrowed by the valve, the amount of the air consumption is made extremely small. Comparing the pilot valve in accordance with the present invention with the conventional displacement type bleed pilot valve, with the same response being maintained, the amount of the air consumption of the pilot valve of the present invention is able to be made less than one tenth of the conventional one. Thus, the primary object of the present invention can be fulfilled. Since the exhaust valve and the air supply valve are made to be freely moved in the output pressure chamber, the valve rod is movable in proportion to the height of the input pressure P_N . Further, the stroke of the valve movement can be made very large. Based on the above construction of the valve rod, the response time is shortened with respect to the conventional pilot valve. Thus, the second object of the present invention can be accomplished.

Further, if the valve rod is made of light metals, it is advantageous in the effect that the valve stroke can easily be made large. Since the amount of the exhaust air is constant whether the input pressure P_N increases or decreases, there is no difference in the operating time or response time of the valve rod between the response time when the valve rod rises upward and that when it moves downward. Thus, the third object of the present invention can be carried out.

FIG. 10 shows a graph of the characteristic curves of the conventional displacement type bleed pilot valve and a pilot valve of the present invention of the semi-bleed displacement type (The amount of bleed is remarkably small in comparison with the conventional bleed type valve.). The reference character Q_0 indicates the amount of the air flow on the output side, Q_A indicates the amount of exhaust (i.e. bleed amount), A indicates a characteristic curve of the relationship between P_N and Q_0 in the conventional pilot valve, B indicates a characteristic curve of the relationship between P_N and Q_0 in the pilot valve of the present invention, (a) indicates a P_N-Q_A curve of the conven-

tional pilot valve, and (b) indicates a P_N - Q_A curve of the pilot valve of the present invention. As apparent from A in FIG. 10, there is no increase in Q_0 even where the P_N is larger than a definite value, and Q_A is decreased to zero where the P_N is increased.

The reason for the above described behavior of the valve of the present invention is that in response to the stabilizing of the input pressure P_N the exhaust valve portion 3 shown in FIG. 1 closes the exhaust valve seat 5 and the amount of the exhaust air becomes zero in the conventional valve. On the other hand, in the pilot valve in accordance with the present invention, the exhaust valve portion 504 and the air supply valve portion 505 are made to freely enter and get out of the output pressure chamber 510 according to the variation in the input pressure P_N . Therefore, there is no shut-off action of the exhaust air in any situation as made in the prior art valve as described above. It will be readily understood, therefore, that the response speed is higher in this invention than the conventional one in the case that the input pressure is exerted on the pilot valve under the equivalent condition. Further, since the amount of the air bleed is constant in the pilot valve of the present invention as described above, the exhaust air will be easily understood to be represented by the curve b.

FIGS. 8A through 8D show various embodiments of the valve portion employed in the pilot valve in accordance with the present invention. In the various embodiments, the reference numeral 803 shows a valve rod, 804 shows an exhaust valve portion, 805 shows an air supply valve portion, and the reference numeral 801 shows the casing of the pilot valve. The shape of the valve and the output pressure chamber may be of any type shown in the FIGS. 8A to 8D. It will be understood that various other shape of the valve and the output pressure chamber may be employed in the variation and modification of the pilot valve of the present invention within the scope of the invention as defined in the claims.

FIG. 9 shows another embodiment of the pilot valve construction in accordance with the present invention, in which the valve seat is made of elastic material.

In FIG. 9, the elements or portions equivalent to those in the valve shown in FIG. 5 are all represented by the equivalent reference numerals used in FIG. 5. A chamber enclosed by a couple of elastic members 905 and 906 is an output pressure chamber. Beside this chamber, all the other components are equivalent to those in the valve shown in FIG. 5. It will be understood that any valve employing an exhaust valve portion or air supply portion made of elastic material is included within the scope of the invention.

Now the construction of the displacement balance type pilot valve accomplishing the fourth object of the present invention will be described.

Generally, in the pneumatic measuring instruments and controllers, fluctuation in the air supply pressure (ordinarily 1.2 to 1.6 kg/cm²) results in fluctuation in the output pressure at the flapper, nozzle and the pilot valve. The measuring instruments or controllers are generally provided with a feedback loop as shown in FIG. 11 in order to improve the linearity and the like. In FIG. 11, the reference character Z indicates an input signal, the reference numeral 111 shows a converting element, 112 a flapper nozzle, 113 a pilot valve and 114 shows a feedback element. The reference charac-

ter P_S shows the air supply pressure, P_N a nozzle back pressure, P_0 the output pressure, and G_t shows the gain of this loop.

Normally, when the air supply pressure P_S is decreased, both the nozzle back pressure P_N and the output pressure P_0 are also decreased. If the gain of the feedback loop G_t is made sufficiently large, the variation in the output becomes smaller as represented by $1/(1+G_t)$. However, if the gain G_t is made large, the system becomes unstable and the possibility of self vibration happens. Accordingly, the value of the gain G_t is limited. This is the same for the case where the air supply pressure is increased.

In the present invention, a pilot valve which will not be affected by the fluctuation in the supply pressure can be provided with a simple construction in a system employing a flapper nozzle and a pilot valve. That is, by properly designing the sectional area of the air supply valve of the displacement type pilot valve, the output pressure is made to increase when the air supply pressure is decreased, and by the increment the decrement due to the flapper nozzle is compensated. Even when the air supply pressure is increased, the similar effect can be obtained.

In FIG. 12, the reference numeral 501 shows a casting, 531 an air supply pressure transmitting tube, 520 an air supply pressure guiding port, 523 an output pressure outlet, 524 an exhaust port, 525 a nozzle back pressure (input pressure) guiding port, 526 and 527 nozzle back pressure transmitting tubes, 509 an air supply chamber, 512 a spring, 505 an air supply valve, 503 a valve rod, 507 an air supply valve seat, 506 an exhaust air valve seat 504 an exhaust valve integrally fixed to the valve rod 503, 510 an output pressure chamber, 508 an input pressure chamber leading to the nozzle back pressure, 502 a diaphragm, 528 a choke, 529 a nozzle, 530 a flapper, P_S an air supply pressure, P_0 an output pressure, P_A atmospheric pressure, and P_N indicates a nozzle back pressure (input pressure). When the nozzle back pressure P_N enters into the nozzle back pressure (input pressure) chamber 508, the diaphragm 502 pushes, by the pressure, the exhaust valve 504, the valve rod 503 and the air supply valve 505 upward in the drawing FIG. 12 and is stopped at a position where the pushing force is balanced with the spring force of the spring 512. According to the spacing between the air supply valve 505 and the valve seat 507 and the spacing between the exhaust valve 504 and the valve seat 506, at the stopped position, the amount of the air supply, output flow and the exhaust flow are determined. Thus, the output pressure P_0 is controlled by the nozzle back pressure P_N . Unless the loaded side of the output pressure P_0 is opened to atmosphere, the following formula is satisfied in the balanced condition

$$P_0 = g(X) \cdot X P_S \quad (1)$$

where $g(X)$ is a function representing the valve characteristic, X is a displacement of the valve, and P_S is an air supply pressure. And X is represented by the following formula

$$X = (P_N A_D - P_S A_V) / S \quad (2)$$

where S is a spring constant, A_D is an effective area of the diaphragm 502 and A_V is area determined by the diameter of the valve seat.

Further, in the case that the output pressure P_0 varies by ΔP_0 when the air supply pressure P_s varies by ΔP_s , the relationship between ΔP_s and ΔP_0 is represented as follows

$$\Delta P_0 = (A_D[\Delta P_N + (\Delta P_0'/K_p)] - \Delta P_s A_v/K_p A_D) \quad (3)$$

where $\Delta P_0'$ is a fluctuation of the output accompanying the increase of the air supply due to the fluctuation in air supply pressure ΔP_s , and ΔP_N is a fluctuation of the nozzle back pressure accompanying the fluctuation in the air supply pressure ΔP_s , and K_p is a gain of the pilot valve.

Though the second term of the formula (2) and the second and third terms of the numerator of the formula (3) have been neglected heretofore, the second term of the formula (2) can be made equal to the first term by properly designing the area A_v . For example, in the case that the air supply pressure P_s is varied by ΔP_s , the nozzle back pressure P_N varies by ΔP_N as shown in FIG. 13A. By the variation ΔP_N of the nozzle back pressure, the output pressure P_0 is varied by ΔP_0 as shown in FIG. 13B. Accordingly, as shown in FIG. 13C, by the variation ΔP_s of the air supply pressure P_s , the output pressure P_0 of the pilot valve is varied by ΔP_{01} due to the influence of the nozzle back pressure. On the other hand, the air pressure fluctuation ΔP_s brings about fluctuation of $-P_{02}$ as shown in FIG. 14.

Size of the valve seats 507 and 506 and the diameter of the choke 528 and the orifice of the nozzle 529 are also the factors of the fluctuation in the output fluctuation due to the air supply pressure fluctuation. As shown in FIG. 15, fluctuation in the air supply pressure causes fluctuation in the nozzle back pressure ΔP_N . In the case that the relationship of the fluctuation ΔP_{01} in the output pressure caused by the above fluctuation in the input pressure and the air supply pressure fluctuation ΔP_s is represented by the curve 101 in the graph in FIG. 15, the relationship between the air supply pressure P_s and the output pressure P_0 becomes as the curve 100 shown in FIG. 15 if a pilot valve is made to have the characteristic as represented by the curve 102 in FIG. 15 by designing properly the effective area A_v determined by the diameter of the valve seat so that the first term of the formula (2) may be cancelled thereby. Thus, a pilot valve in which the output pressure P_0 is maintained constant regardless of the fluctuation of the air supply pressure P_s within the practical range of the pressure can be obtained as shown a fat line L in FIG. 15.

As described above, in accordance with the present invention there is provided a pilot valve of this kind in which the output pressure is not affected by the fluctuation in the air supply pressure only by designing the sectional area of the supply valve as described above.

Further, in the pilot valve in accordance with the present invention, the volume of the whole valve can be reduced to one fifth as small as the conventional valve since the shape of the valve is made compact by being made a sluice shape. In addition, since the stroke of the movement of the valve can be made large, the efficiency of transmitting or feeding out the output air can be increased.

As hereinabove described, in accordance with the present invention, the air consumption is remarkably reduced to improve the valve in the sense of economy, and further the response performance is improved and

the response time is made constant whether the input pressure increases or decreases. Thus, the improvement of the displacement type semi-bleed pilot valve brings about an improvement in the stability in the process control and improvement in the controlling ability.

Furthermore, in a system employing a flapper nozzle and a pilot valve, an improved pilot valve of this kind can be obtained in accordance with the present invention in which in the range where the value of $\Delta P_N/\Delta P_s$ is approximately constant the output pressure is not affected by the fluctuation in the air supply pressure by designing the air supply valve 505 and the effective sectional area A_v of the spacing at the valve seat 507 to satisfy the relationship as $A_v = P_N A_D / P_s$, where P_N is a nozzle back pressure, A_D is an effective area of the diaphragm 502, and P_s is a predetermined air supply pressure.

What is claimed is:

1. A displacement type pilot valve comprising a casing including an input pressure chamber into which input pressure is introduced, an air supply pressure chamber into which an air supply is introduced, an output pressure chamber for receiving the air supply from the supply pressure chamber and transmitting an output pressure in proportion to the input pressure, and an exhaust chamber separated from the input pressure chamber with a diaphragm, the exhaust chamber being in communication with the output pressure chamber and with atmospheric pressure; a valve rod means including an exhaust valve fixed at an end thereof to the diaphragm and forming an exhaust passage leading from the output pressure chamber to the exhaust pressure chamber, an air supply valve forming an air supply passage leading from the air supply pressure chamber to the output pressure chamber and a valve rod extending between the exhaust valve and the supply valve; and a valve rod pushing spring to urge the valve rod disposed in the air supply pressure chamber toward the diaphragm, the output pressure chamber having at least one of a wall portion and a valve seat in the region of the exhaust passage for cooperation with the exhaust valve and at least one of a wall portion and a valve seat in the region of the air supply passage for cooperation with the air supply valve, the supply valve having an outer diameter which is slightly smaller than the inner diameter of the at least one cooperating valve seat and wall portion and the exhaust valve having an outer diameter which is slightly smaller than the inner diameter of the at least one cooperating valve seat and wall portion to provide a flow of air between the output pressure chamber and at least one of the air supply chamber and the exhaust chamber in all positions of the exhaust and supply valves.

2. A displacement type pilot valve as defined in claim 1 wherein at least one of the exhaust valve and the air supply valve of said valve rod is normally opened to a degree corresponding to the input pressure.

3. A displacement type pilot valve as defined in claim 1 wherein said valve rod is made of light metals.

4. A displacement type pilot valve as defined in claim 1 wherein the formula $A_v = P_N A_D / P_s$ is satisfied, where A_v is an effective sectional area of the air supply valve and the spacing between the supply valve and the valve seat therefor, P_N is an input pressure, A_D is an effective area of the diaphragm and P_s is an air supply pressure.

5. A displacement type pilot valve comprising a casing including an input pressure chamber into which

input pressure is introduced, an air supply pressure chamber into which an air supply is introduced, an output pressure chamber for receiving the air supply from the supply pressure chamber and for transmitting an output pressure in proportion to the input pressure, and an exhaust chamber separated from the input pressure chamber by a diaphragm, the exhaust chamber communicating with the output pressure chamber and with atmosphere, movable valve means connected to the diaphragm and extending from the exhaust chamber through the output chamber and into the air supply chamber, spring means arranged in the air supply chamber for biasing the valve means extending into the air supply chamber toward the diaphragm, the valve means venting a portion of the air supply to atmosphere in all positions of the valve means, and the valve means being freely movable with respect to the output pressure chamber.

6. A displacement type pilot valve as defined in claim 5, wherein the movable valve means includes an exhaust valve having one end thereof secured to the diaphragm, an air supply valve being biased by the spring means, and a valve rod extending between the exhaust

valve and the air supply valve.

7. A displacement type pilot valve as defined in claim 6, wherein at least one of the exhaust valve and the air supply valve varies at least one of the portion of the air supply vented to atmosphere and the portion of the air supply provided as an output of the output pressure chamber in accordance with the input pressure.

8. A displacement type pilot valve as defined in claim 6, wherein the output pressure chamber is provided with at least one of a wall portion and a valve seat for cooperation with the exhaust valve, and at least one of a wall portion and a valve seat for cooperation with the air supply valve.

9. A displacement type pilot valve as defined in claim 8, wherein the exhaust valve and the air supply valve are dimensioned to define a narrow communicating passage between the output pressure chamber and at least one of the exhaust chamber and the air supply chamber when the exhaust valve and the air supply valve are directly adjacent the respective cooperating wall portion and valve seat of the output pressure chamber.
